UNITED STATES PATENT OFFICE

91,722

DESIGN FOR AN INCANDESCENT LAMP

George W. Pedersen, Aurora, Colo.

Application November 3, 1933, Serial No. 49,646

Term of patent 7 years

To all whom it may concern:

Be it known that I, GEORGE W. PEDERSEN, a citizen of the United States, residing at Aurora, in the county of Adams and State of Colorado, have invented a new, original, and ornamental Design for an Incandescent Lamp, of which the following is a specification, reference being had to the accompanying drawing, forming part thereof.

Fig. 1 is a side elevation of an incandescent lamp showing my design and looking in the direction of arrow 1, Fig. 3;

Fig. 2 is a side elevation of an incandescent lamp showing my design and looking in the direction of arrow 2, Fig. 3;

Fig. 3 is a top plan view of the incandescent lamp; and

Fig. 4 is a perspective view of the incandescent lamp.

I claim:

The ornamental design for an incandescent lamp, as shown.

In testimony whereof I affix my signature.
GEORGE W. PEDERSEN.
